UNITED STATES PATENT OFFICE.

ALPHONSO S. CAMPBELL, OF MEDFORD, MASSACHUSETTS.

BINNACLE-LAMP AND CONNECTIONS.

1,058,032.

Specification of Letters Patent.

Patented Apr. 8, 1913.

Application filed June 14, 1910. Serial No. 566,755.

To all whom it may concern:

Be it known that I, ALPHONSO S. CAMPBELL, a citizen of the United States, and a resident of Medford, in the county of Middlesex, State of Massachusetts, have invented an Improvement in Binnacle-Lamps and Connections, of which the following description, in connection with the accompanying drawings, is a specification, like letters 10 on the drawings representing like parts.

This invention relates to binnacle lamps and electrical connections therefor and among other objects aims to provide an electric lamp for effectively illuminating the 15 ship's compass with economy of light and power.

The character of the invention may be best understood by reference to the following description of an illustrative embodiment thereof shown in the accompanying drawings, wherein:

Figure 1 is a perspective of a binnacle equipped with an electric lamp and connections embodying my invention; Fig. 2, on 25 an enlarged scale, is a vertical section through the lamp and its connections; and Fig. 3 is a view looking toward the right from line 5—5 of Fig. 2.

Referring to the drawings, in Fig. 1 is shown a binnacle comprising a box 1 of usual construction having in its after side an inclined window 2 for disclosing a mariner's compass³ which may be mounted 30 within the binnacle in the usual manner.

Heretofore, so far as I am aware, binnacles have been usually lighted by oil lamps placed within the binnacle and arranged to diffuse their light throughout the interior thereof. Such an oil lamp is objectionable for many reasons. Among 40 others it is apt to smell bad, does not give a steady light and must be kept lighted throughout the night. Furthermore, a light generally distributed throughout the interior of the binnacle causes objectionable reflections from the compass to the eye of the observer which renders the reading of the compass difficult and uncomfortable.

By my invention the above and other objections are eliminated by an electric lamp provided with means for directing or focusing its light directly on to the compass without illuminating the entire interior of the binnacle and without the objectionable 55 reflections referred to. To this end the light

is mounted in the binnacle above the compass and in one of the side walls thereof, preferably so that the center of the light will be equal distances to one side of the center of the compass and above the latter. 60

Herein is shown an incandescent lamp 5 having a base 7 threaded into a socket 9 of brass or other suitable conductive material having a flange 11 which may be secured by screws 13 to a bell shaped casing 15 65 herein of brass said casing in turn being secured by screws 17 to an exterior wall of the binnacle. To direct the light from the lamp 5, on to the compass, said lamp may be inclosed in a bulb-like hood 19 having an interior surface of reflecting material, said hood terminating in a cylindrical portion 21 adapted to be slid on to the socket 9 and be held in its positions of adjustment by a suitable set screw 23 threaded into said bell 70 casing 15. To magnify the light coming from the lamp and focus its rays on the compass, the end of the reflector bulb 19 may be truncated and receive a lens 25. By 75 adjusting the reflector bulb on the socket 80 9 the lens will be caused to approach or recede from the lamp more or less to focus or direct the rays of light laterally on to the face of the compass as shown in Fig. 1. As a result the rays extending from the 85 laterally positioned lamp will not be reflected objectionably into the eyes of the observer and will provide just enough light placed only where necessary. This localizing of the light and the magnifying thereof 90 had by the lens 25 permits the compass to be sufficiently illuminated with a minimum low voltage and amperage thereby providing a light of maximum efficiency and economy. By thus localizing and magnifying 95 the light the current required is so small that it does not disturb the compass needle.

One of the great objections encountered in the use of electrical devices in marine work consists in the corroding action which the salt air has upon electrical contact surfaces. This corrosive action destroys the brightness of the contacting parts and as a result diminishes the efficiency of electrical equipment if not entirely incapacitating the 100 same. One of the principal objects of my invention is to provide an electrical make and break connection for said lamp whereby the contacting surfaces are always maintained bright and clean without the objec- 105 110

tions referred to. Herein this connection comprises a contact carrying socket conveniently formed by a sleeve 27 of insulation material tightly fitted into a counterbore in the socket 9 referred to. Within this sleeve is a disk 29 of insulating material carrying a contact pin 31 having a head for engagement with a contact in the lamp base 7 when the latter is screwed into the socket, and a pointed end for a purpose hereinafter described. The other socket contact herein comprises a spring pressed catch 33 mounted in a cup 34 of conductive material positioned transversely to the sleeve 27 and adapted to be projected through an aperture 35 in the latter. Coöperating with the contact carrying socket described is a contact carrying plug 37 cylindrical in its general form and comprising a small central tube contact 39 of brass or other suitable conductive material adapted to receive the pin contact 31 referred to. To cause this tube intimately to engage said pin said tube may be split at its upper end to provide for expansion on the entrance of said pin therein. The opposite end of said tube may be soldered or otherwise secured to a wire 41 leading to a battery, magneto or other suitable source of electricity. Encircling the tube contact described is a second contact 42 also of tubular form and sufficiently large to permit the introduction of a rubber or other insulating sleeve 43 between said tubes. A wire 45 may be soldered or otherwise secured to an end of this contact and led to the battery or other suitable source of electricity. The large tube contact is inclosed by a coating 47 of rubber or other insulating material with the exception of a portion of said tube. This portion is thickened as at 48 to extend outwardly with a thickness equal to the insulation coating 47, thereby forming a cylindrical end of the plug which will present an external surface partially of conductive and partially of non-conductive material. This cylinder is of a proper diameter accurately to fit in the socket sleeve 27. To lock the plug in the socket the former is provided with a circumferential groove 49 having a straight wall and an inclined wall. When the plug is inserted in the socket, a beveled end of the catch 33, referred to, will ride over the end of the plug and under the action of its spring will seat itself back of a shoulder of the flange 50 formed by the circumferential groove in said plug. When in this position it will be apparent that withdrawal of the plug from said socket will be prevented. To prevent a circuit breaking separation of the plug and socket prior to a relative wiping movement of said parts the plug may only be withdrawn from the socket after the catch has rotated past the conductive portion of said plug into engagement with the non-conduc-

tive portion thereof. When the plug has been turned to bring it in such position, to permit its withdrawal the non-conductive coating of said plug may be slabbed off as at 51 presenting a flat face in line with the base of the circumferential groove of the plug so that when the plug is in a position with the catch opposite its flat face the straight edge of the catch may readily wipe over the end of the plug without hindrance to the withdrawal of the latter. Thus it will be seen that each time the plug is separated from the socket said plug must first be turned to cause the catch to wipe or rub past the conductive portion of said plug in order that the latter may be brought into a position to bring its non-conductive portion in alinement with said catch and with its flat face 51 in alinement with said catch. The constant wiping of the groove and catch contacts and the pin and hollow tube contacts past one another made necessary each time that the plug is detached or each time that the lamp is turned on or off maintains the contacting surfaces constantly clean and bright insuring an effective electrical connection irrespective of the corroding action of the salt air. The plug may be inclosed by a housing 53 of rubber or other suitable material which may have a knurled periphery 54 to facilitate the turning of said plug for making and breaking the circuit. To prevent the wires connected to the plug contacts from pulling out of said plug the wires preferably are first connected to said contacts and then the insulating coating 47 may be formed or molded around said wires and pressed into intimate engagement therewith so that when the coating hardens it may nip the insulation of said wires and prevent withdrawal from said housing. As shown herein the current on the wire 41 may pass from the central small tube plug contact to the socket pin contact 31 through a contact in engagement with the head of said pin projecting into the lamp and connected to the filament of the latter. The current in returning may pass through the lamp base to the socket 9 thence through the catch recess to the catch 33, thence to the thickened, exposed portion of the larger tube contact of the plug to the other wire 45. It will be understood that if desired instead of returning the current through the base of the lamp and the socket as described the filament may be connected by a wire directly to the contact catch 33. To indicate when the flat face of the plug flange is opposite the catch 33 the plug housing may be provided with a knob 59 in alinement with the flattened face of the plug flange. By this separable plug and socket contact connection it will not be necessary to maintain the light continuously lighted throughout the night but whenever it is desired to observe the compass it is

merely necessary to give the knurled plug a slight turn to complete the circuit to the lamp.

Having described one embodiment of my 5 invention without limiting myself thereto what I claim as new and desire to secure by Letters Patent is:

The combination of a casing, a compass mounted therein, a housing for external attachment to said casing, a detachable contact connection for said housing, an electric lamp adapted for power sufficiently small to avoid disturbing the needle of the compass, a hood projecting from said housing 15 into said casing and formed to receive said

lamp and localize the light thereof to said compass, and a lens in said hood for magnifying said light sufficiently to permit a ready visualization of the compass, said hood having provision permitting the adjustment thereof relatively to its housing to vary the location of the light.

In testimony whereof, I have signed my name to this specification, in the presence of two subscribing witnesses.

ALPHONSO S. CAMPBELL.
